UNITED STATES PATENT OFFICE.

JOHN H. LARMONT, OF MONTREAL, QUEBEC, CANADA, ASSIGNOR OF ONE-HALF TO
VICTOR C. ARMSTRONG, OF HACKENSACK, NEW JERSEY.

ANTICREEPER FOR RAILWAY RAILS.

Application filed July 19, 1922. Serial No. 576,166.

To all whom it may concern:

Be it known that I, JOHN H. LARMONT, a subject of the King of England, residing at Montreal, in the Province of Quebec, Canada, have invented certain new and useful Improvements in Anticreepers for Railway Rails, of which the following is a specification.

This invention relates to anti-creeping devices of anchors for railway rails, and more particularly to a device for preventing creeping of the rails in either direction.

A primary object of the invention is to provide a device which affords a maximum anchorage by distributing the creeping forces of the rail over adjacent ties, thereby not only obtaining the advantage of additional ballast resistance afforded by more than one tie, but also more effectively checking the creeping movement of the rail in both directions. In that connection the invention contemplates a device which includes tie plates joined or connected in a thoroughly practical and reliable manner, thereby providing an anchor having adequate tie-bearing surfaces, while the means for joining or connecting the tie-plates is connected to the rail web in such a way that the tendency of the rail to move is transmitted directly to the tie-plates which are secured to the ties by a plurality of spikes or equivalent fastenings.

A further object of the invention is to provide an anti-creeping device that may be readily manufactured by rolling, or by utilizing readily and conveniently available materials, thereby effecting considerable economy of production, while at the same time providing a strong, durable and reliable device.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings in which—

Figure 1 is a side elevation of the improved anti-creep.

Figure 2 is an end elevation thereof.

Figure 3 is a top plan view partly in section.

Figure 4 is a view similar to Figure 3 showing a modification of the invention.

Figure 5 is a detail view further illustrating the modification shown in Figure 4.

Figure 6 is a side elevation of a further modification of the invention.

Figure 7 is a detail sectional view taken on the line 7—7 of Figure 6.

In carrying the present invention into effect it is proposed to provide an anti-creep 65 essentially comprising a pair of tie-plates T and T' connected by an intermediate rail-engaging strap S which may be connected to the web of the rail in such a manner as to effectually cause any creeping movement 70 thereof to be transmitted directly to the tie-plates T and T'. In its general aspect, therefore, the present invention aims to provide an anti-creeping device comprising a pair of tie-plates adapted to be positioned 75 on adjacent ties and not only connected to each other, but also rigidly secured to the rail.

Obviously, this general type of anti-creep may be produced in various ways, 80 but a practical illustration thereof is shown in Figures 1 to 3 wherein the device is preferably made by rolling process, so that the tie-plates T and T' and strap S are integral. That is to say, the tie-plate stock may 85 be rolled in strips and then cut into the proper lengths, after which the central portion thereof may be cut away leaving the marginal edge or rail-engaging strap S. This strap may then be bent upwardly from the plane of the base of the tie-plates until the intermediate portion thereof assumes a vertical position parallel to the rail web. The bending up of this strap may be accomplished by any of the usual and well-known 95 forging operations employed in the making of devices of this character, and, after the strap has been formed, the web may be provided with a suitable opening 1 to receive a bolt 2 for fastening the same to the web 100 w of the rail R.

In connection with the tie-plate portions T and T' of the device, it will be observed that the same are provided with the parallel ribs 3 and 4 which receive the base of the 105 rail therebetween. The purpose of these

ribs is to grip or bind against the rail flanges when and if the creeping of the rails causes the ties to twist or move due to the creeping movement. That is to say, when the tie-plates are secured to the ties by spikes driven through the openings 5, it will be apparent that any tendency of the rail to creep and throw the ties out of alinement in the ballast will result in the ribs 3 and 4 exerting a binding or gripping effect on the edges of the rail base, thereby to provide a further and augmented check against creeping in addition to that afforded by the engagement of the strap S with the web of the rail through the medium of the bolt 1.

If desired, the invention may be also carried out by utilizing separate previously formed tie-plates T² in connection with a strap S' of any suitable and conveniently available material, the opposite ends S² of which may be connected to the outer flange portions T³ of the tie-plates by a suitable welded joint S³, as clearly shown in Figures 4 and 5 of the drawings. In this form of the invention it will, of course, be understood that the intermediate portion of the strap S' is connected to the rail web by a bolt or equivalent fastening as in the case of Figure 1.

A further modification of the invention is shown in Figures 6 and 7 of the drawings wherein it will be observed that the tie-plates T⁴ are provided with the downturned tie-abutting flanges T⁵ at their inner adjacent edges, thereby providing a relatively wide bearing against the edge of the ties which materially assists in holding the plates in position and relieving the spikes or other fastenings of some of the shearing stress imposed thereon due to the tendency of the rail to move or creep. The said tie-abutting flanges T⁵ are preferably formed integral with the tie-plates at the time of manufacture, but, it will of course be understood that the same may be applied thereto by any of the conventional and well-known types of welding processes, now generally recognized as available for the purpose, if desired.

From the foregoing it will be apparent that the novel and distinctive features of the present invention reside in the provision of an anti-creeper consisting of spaced tie-plates having upstanding parallel ribs for engaging with the edges of the base flanges of the rail, and also having a connecting strap whose intermediate portion engages with the rail web, thereby to positively transmit the creeping movement of the rail to the tie-plates, whereby the latter in turn will distribute the strain to the tie and produce the effect of causing the ribs to bind

or bite against the edges of the rail thereby providing a most effectual resistance to creeping.

I claim:

1. A rail anchor including a pair of tie plates, connecting means for the tie plates, and means for securing the connecting means to the web of the rail.

2. A rail anchor including a pair of spaced tie plates, an intermediate rail engaging member integral therewith and rigidly connecting the said tie plates, and means for securing said rail engaging member to the web of the rail.

3. A rail anchor including a pair of spaced tie plates, an intermediate rail engaging member connecting the same, said tie plates having shoulders for abutting with the flanges of the rail, and means for securing said rail engaging member to the web of the rail.

4. A rail anchor including a pair of spaced tie plates, an intermediate rail engaging member connecting the same, said tie plates having spaced parallel shoulders for engaging with opposite sides of the rail flange, and means for securing said rail engaging member to the web of the rail.

5. A rail anchor including a pair of spaced tie plates, an intermediate rail engaging member connecting the same, said tie plates having inner and outer spaced parallel ribs receiving and engaging the edges of the opposite base flanges of the rail, and means for securing said rail engaging member to the web of the rail.

6. A rail anchor including a pair of spaced tie plates, an intermediate strap member connecting said plates and having its intermediate portion thereof secured to the web of the rail.

7. A rail anchor including a pair of tie plates, a strap member connecting the outer edges of said tie plates and having its intermediate portion lying in a substantially vertical plane, and means for connecting the intermediate portion of the strap with the rail web.

8. A rail anchor including tie plates connected by an intermediate rail engaging strap, means for connecting said rail engaging strap to the web of the rail and adjacent edges of said tie plates lying beneath the rail having downturned tie abutting flange portions.

In testimony whereof I hereunto affix my signature.

JOHN H. LARMONTH.
